ROAD MILLER

Edward C. Gledhill, Galion, Ohio

Application August 3, 1938, Serial No. 222,915

10 Claims. (Cl. 37—108)

This invention relates to an improved road miller.

One of the objects of my present invention is to provide a road miller which will be effective in operation for milling down a road surface so that undesirable uneven surfaces or obstructions thereon will be removed.

Another object of the invention is to provide a road miller having a motor driven rotor with 10 milling teeth thereon, which rotor may be adjusted so that the depth of cut of the milling teeth may be varied to suit particular conditions.

A further object of the invention is to provide a road machine of this character wherein the 15 rotor teeth are so mounted that, should one or more of them engage an obstruction too deep set to be removed and too hard to be milled down, said tooth will be permitted to stop and to slip on the rotor shaft with the result that injury to the affected tooth will be avoided and operation of the 20 unobstructed teeth will not be affected.

As a further object, the invention seeks to provide a road miller having a main frame, a sub-frame, and a milling rotor, the sub-frame and 25 milling rotor being movable as a unit with respect to the main frame, into and out of operative position, and the milling rotor being adjustable on the sub-frame.

A still further object of the invention is to provide a road miller having mounted on the main 30 frame thereof a power plant and transmission which will be operable for rotating the rotor at the desired rate of speed for any particular road milling operation.

The invention contemplates other objects 35 which will become apparent during the course of the following description.

My invention is illustrated in the accompanying drawings forming a part of this application.

40 In the drawings:

Figure 1 is a side elevation of my improved road miller.

Figure 2 is a top plan view of the machine.

Figure 3 is an enlarged detail side elevation 45 showing particularly the adjustable mounting for the rotor and driving means therefor.

Figure 4 is a vertical sectional view on the line 4—6 of Figure 1.

Figure 5 is a detail top plan view showing one 50 of the milling teeth employed.

Figure 6 is a longitudinal sectional view of one of said milling teeth.

Figure 7 is a vertical sectional view on the line 7—7 of Figure 6.

55 Referring now more particularly to the draw-

ings, wherein similar numerals of reference will be seen to designate like parts throughout the several views, reference is first had to Figures 1 and 2 of the drawings. The numeral 1 indicates, in general, the main frame of my improved road miller. The main frame includes channelled supporting members 2 and 3 which are disposed in parallel spaced relation and extend throughout the major portion of the length of the machine. The members 2 and 3 are connected at their corresponding forward ends by a front brace or fore-hound 4. Pivotally mounted on the front brace 4 is a front wheel assembly 5 having a tongue 6 connected therewith. The tongue is intended for connection with a truck or other source of tractive effort.

At the rear, the members 2 and 3 of the main frame are provided with braces 7 which are fixed at their corresponding lower ends to a rear axle 8. The rear axle is provided with rear wheels 9 and 10 rotatably mounted on the free ends thereof. Braces 11 extend from the axle obliquely upwardly and are secured to the members 2 and 3 forwardly of their corresponding rear ends.

Mounted between the members 2 and 3 between 25 their midportions and corresponding forward ends, is a power plant 12 which, in the present instance, comprises an internal combustion engine, although it should be understood that an electric motor may be employed if found practicable and desirable. A hood 13 overhangs the motor and provides shelter therefor. A gasoline supply tank is shown at 14 and a transmission lever at 15. The transmission lever is, of course, connected to the transmission 16 of the power 30 plant 12 and is adapted to control motion of said power plant.

Associated with the main frame 1 is a sub-frame 18. The sub-frame includes runner frames 19 and 20. As best seen in Figure 2, the runner frames are located in parallel spaced relation at opposite sides of the main frame. Inasmuch as said runner frames are identical in construction, a description of one will suffice for both. A typical runner frame includes a substantially inverted 45 U-shaped sub-frame member 21 having a straight portion 22 and inclined end portions 23 which have their corresponding lower ends connected to runners 24. Vertically disposed braces 25, 26, 27 and 28 connect the runners 24 with the sub-frame 50 member 22 and provide a rigid runner frame structure.

Mounted on the runner frame, medially of the length thereof, are guide posts 29 and 30 which are vertically disposed and slidably mount a ver-

5 tically adjustable carriage 31. The carriage 31 includes a web 32 and a hub portion 33, which web is formed with a vertical projection 34 adapted to have mounted therein a nut 35 which 5 is internally threaded to receive the shank 36 of an adjusting bolt 37 formed with a manually engageable wheel 38, which wheel and bolt are threaded through the straight portion 22 of the inverted U-shaped sub-frame member 21. It 10 will be understood that rotation of the bolt 37 will effect raising and lowering of the carriage 31 on the guides 29 and 30.

15 The runner frames 19 and 20 are connected with the central portion of the sub-frame 18 by means of a plurality of levers. By referring particularly to Figure 2 of the drawings, it will be seen that the sub-frame includes cross members 39 and 40 which are welded or otherwise secured to the members 2 and 3 of the main 20 frame and are disposed in parallel spaced relation to each other. The cross members 39 and 40 are connected at their free ends by rods 41 and 42 which rods are rotatably mounted at their corresponding ends in the corresponding free 25 ends of the members 39 and 40. The rods 41 and 42 have levers 43 fixed thereto, which levers comprise parallel spaced members 44 and 45. It will be seen that the rods 41 and 42 each have one of these levers 43 at each of their corresponding end portions and these levers 43 are 30 pivotally connected with the runner frame by relatively long levers 46 which have their lower corresponding ends pivotally connected to the runner frame by means of yokes 47. Medially 35 of the length of the rods 41 and 42 there are mounted raising levers 48 and 49.

40 Mounted on the main frame 1 between the cross members 39 and 40 are jack supporting beams 50 and 51 substantially L-shaped in formation. The beams have extending therebetween the guide rods 52 and 53. A hydraulic jack cylinder 54 is carried by the beam 51 and has a piston rod 55 extending through one end thereof in parallel spaced relation to the guide 45 rods 52 and 53. A cross head 56 is carried on the end of the piston rod 55 and has its free ends slideable on the guide rods 52 and 53. Pulleys 57 and 58 are mounted on brackets 59 (see Figure 4) and said pulleys have trained thereabout 50 cables 60 and 61. The cables have corresponding inner ends connected with the cross head 56 and corresponding outer ends connected with the levers 48 and 49. A source of hydraulic pressure is shown in Figure 1 at 62 and this source of 55 pressure is, of course, connected with the cylinder 54.

55 It will be understood that when the jack cylinder 54 has hydraulic pressure introduced therein, the piston rod 55 will be urged outwardly for forcing the cross head forwardly toward the member 53. The cables 60 and 61 will be pulled about the pulleys 57 and 58 for rocking the raising levers 48 and 49 inwardly, when the rods 41 and 42 will be rotated and the levers 43 and 46 60 will be lifted for lifting the runner frames clear of the ground so that the wheels 5, 9 and 10 will be allowed to support the machine for transporting the same from place to place. When it is desired to lower the runner frames it is only 65 necessary to reduce the hydraulic pressure, when the weight of the runner frames will cause the levers to be pulled in an opposite direction and the cross head and piston rod to move toward the jack cylinder 54 in inoperative position.

70 For effecting the actual road milling operation,

I employ a rotor, shown generally at 63. The rotor includes a shaft 64 which has its opposite end portions extending through the corresponding free end portions of the mounting frame, shown generally at 65. The shaft 64 extends 5 further into the hub portion 33 of the carriage 31 of the runner frames 19 and 20. Mounted on the shaft 64 between the ends of the mounting frame are milling teeth 66. The milling teeth are of identical construction and in view 10 of this fact a description of a typical milling tooth will be sufficient to embrace all of said teeth. The construction and mounting of a typical tooth is shown in Figures 5, 6 and 7 of the drawings. It will be seen that the milling tooth 66 comprises tooth sections 67 and 68 each of which comprises one-half of a tooth. The sections 67 and 68 are adapted to fit about the shaft 64 in close frictional engagement therewith and in such a manner that should one of the teeth strike an obstruction, said tooth will be permitted to stop and operation of the remaining teeth on the shaft, as well as rotation of the shaft 6, will not be affected. The tooth sections 67 and 68 are substantially hemispherical in cross section and substantially rectangular in top plan (see Figure 5 of the drawings). The sections each include tooth members 69 extended in opposite directions in the same longitudinal plane and in planes parallel with each other. The tooth members 69 comprise flat portions 70 and web portions 71 and 72, which web portions are tapered from a point on the surface of the members toward the free ends of the tooth members. The tooth sections are connected to 20 each other by means of bolts 73, preferably four in number. The bolts extend through corresponding flanges on one tooth section into mating flanges on the other tooth section, it being understood that certain of the bolts pass through 25 the flat portions 70 of the tooth members 69. Springs 74 surround the free end portions of the bolts 73 and have washers 75 and nuts 76 bearing thereagainst. It will be seen that by tightening the nuts 76, the spring 74 will be compressed and 30 the tooth sections 67 and 68 drawn toward each other and into tight frictional engagement with the shaft 64. The tooth members 67 and 68 are undercut at their free end portions, as shown at 35 77, and define pockets terminating in shoulders 40 78. The pockets receive tooth points 79 and said tooth points are held in place in the pockets by bolts 80 and nuts 81. The tooth points 79 are 45 preferably rectangular in shape and are formed of very hard metal. These tooth points are, of course, adapted to engage the surface to be milled and must, necessarily, be of such formation as to withstand resistance and shocks offered by obstructions to be milled. It will be 50 observed that each tooth 66 is formed with two 55 tooth points and that the points are arranged in planes parallel with each other so that a complete rotation of a tooth will effect the cutting or milling of a path equivalent to the width of the entire tooth. Bushings 82 and 83 are carried 60 on the shaft 64 and serve to retain the teeth 66 in proper relative position on the shaft. Mounted on the shaft 64 adjacent the free end 65 portions of the mounting frame 65, are sprocket wheels 84 and 85, the purpose of which will be 70 presently described.

The mounting frame 65 is best shown in Figures 2, 3 and 4 of the drawings, and comprises mounting bars 86 and 87. The mounting bars are formed from inverted L-shaped metal members 75

and include obliquely disposed straight portions 88 and 89 which terminate at their inner corresponding ends in straight connecting portions 90 and 91, which portions 90 and 91, as seen in Figures 1 and 3, are formed with longitudinally extending slots 92. The connecting portions 90 and 91 are disposed in parallel spaced relation to each other and in straddling relation to a universal joint 93 which is connected with the transmission 16 of the motor 12. The universal joint has extending laterally therethrough a connecting pin 94 which is slidably engageable in the slots 92 of the straight portions 90 and 91. The obliquely disposed portions 88 and 89 terminate in straight free end portions 95 and 96. The free end portions, as heretofore described, journal the end portions of the shaft 64 and bearings 97 and 98 are formed on the free ends of said portions 95 and 96 for the purpose of effecting the journaling of said shaft ends. Mounted on the free end portions 95 and 96 and the bearings 97 and 98 are bearing standards 99 and 100. A typical bearing standard, as best seen in Figure 3, comprises substantially vertically extending portions 101 and 102 connected by a web 103. A flat upper surface 104 is provided for the top of the bearing standard. Bearings 105 and 106 are carried on the flat upper surfaces 104 of the bearing standards and journal the free ends of driving shafts 107 and 108 which form part of a differential mechanism 109. The differential mechanism includes a housing 110 and shaft housings 111 and 112. Fixed on the shafts 107 and 108, between the end portions of the shaft housings 111 and 112 and the bearings 105 and 106, are driving sprockets 113 and 114 which, as will be noted, are disposed in vertical alinement with the sprockets 84 and 85 on the shaft 64. Sprocket chains 115 and 116 operatively connect the sprocket 113 with the sprocket 84 and the sprocket 114 with the sprocket 85, respectively. A torque tube 117 is connected with the differential housing and extends forwardly in close proximity with the universal joint 93. The torque tube 117 houses a driving shaft 118 which is, of course, connected to the universal joint.

The operation of the invention should be understood from the foregoing description but a brief discussion of the operation is not thought to be out of place. My improved road miller is first connected to a source of motive power by means of the tongue 6 and is drawn to the area to be milled, it being understood, of course, that during transportation the runner frames, together with the milling rotor, will be disposed out of contact with the ground. When the machine is ready for use, the runner frames are lowered, in the manner heretofore described, and the rotor mounting frame is swung downwardly for engaging the rotor with the surface to be milled. In view of the fact that the end of the shaft 66 is carried in the carriage 31, movement of the rotor will be limited to the vertical. The slot 92, of course, permits a slight inward shifting movement of the mounting frame which would be occasioned by vertical and not arcuate movement of the carriage 31. The depth of cut of the rotor teeth 66 is, course, regulated by shifting the carriages 31 with respect to the runner frames by means of the bolts 37. After the motor 12 is started and the transmission lever is thrown into operative position, the sprocket chains 115 and 116 will be caused to transmit rotative movement from the shafts 107 and 108 to the shaft 64, when the teeth 66 will be caused to bite into the surface

to be milled for effecting the milling operation. Should one of the teeth encounter an object too deeply set or too hard to be milled, said tooth will stop and slip about the shaft 64 until said obstruction has been cleared. When this takes place, however, the remaining teeth will continue to operate properly on the shaft 64 so that but one of the teeth, i. e., the tooth obstructed, will be affected. After the milling operation has been completed, the hydraulic mechanism 62 may be actuated for raising the runner frames and, therewith, the rotor shaft and teeth, when the machine may be hauled away.

Although my improved road miller is intended to be attached to a source of power, during a milling operation, it has been found that rotation of the shaft 64 and constant engagement of the milling teeth with the ground will cause the machine to move over the ground while a milling operation is taking place and without regard to the source of pulling power. It is believed that the construction and operation of my improved road miller will now be thoroughly understood so that further description is unnecessary.

Having thus described the invention, what I claim is:

1. In a road miller, a main frame having wheels and a tongue to be connected to a source of motive power, a motor carried by the main frame, a sub-frame carried by the main frame and having rods, runner frames, levers operatively connecting the runner frames with the rods on the sub-frame, hydraulically operated means carried by the main frame and operatively connected with certain of the levers for raising or lowering the runner frames with respect to the sub-frame and main frame and to a surface to be milled, a mounting frame swingingly connected with the motor, a rotor having a shaft journaled in the mounting frame and in the runner frames, teeth carried by the rotor, bearings carried by the mounting frame and disposed above the ends of the rotor, a differential mechanism carried by the mounting frame and having shafts journaled in the bearings, said differential mechanism having a drive shaft connected with the motor, means operatively connecting the differential shaft with the rotor whereby rotative movement from the motor will be transmitted to the rotor shaft for engaging the teeth with a surface to be milled, and means for adjusting the rotor shaft and teeth with respect to the runner frames thereby adjusting the depth of cut of the teeth.

2. In a road miller, a main frame having parallel bars and a fore-hound, wheels carried at the forward end of the frame, wheels carried at the rear end of the frame, a motor carried by the frame between the bars and having a transmission and a universal joint, a sub-frame, runner frames associated with the sub-frame, means for raising and lowering the runner frames with respect to the sub-frame and a surface to be milled, a mounting frame having members swingingly connected with the universal joint, said members having free end portions connected with the runner frames, bearing standards carried by the members of the mounting frame and having bearings thereon, a differential having shafts journaled in the bearings, a rotor carried by and extending between the runner frames, means operatively connecting the rotor with the differential shafts, teeth carried by the rotor for effecting a milling operation when in motion, a drive shaft connecting the differential shafts with the motor.

and means for adjusting the mounting shaft and rotor with respect to the runner frames whereby the depth of cut of the rotor teeth may be adjusted to suit conditions.

5. 3. In a road miller, a main frame, a motor carried thereby, a sub-frame, runner frames associated with the sub-frame, said sub-frame including runners and substantially inverted U-shaped sub-frame members, said runner frames 10 having braces and spaced guide posts, carriages carried by and extending between the guide posts, a mounting frame connected with the motor and having end portions disposed adjacent the carriages, a rotor having a shaft extending through 15 the end portions of the mounting frame and into the carriages, an adjusting bolt for shifting the carriages on the guide posts whereby the rotor shaft will be raised or lowered with respect to the runner frames and the mounting frame will 20 be swung with respect to the main frame and motor, teeth carried by the rotor shaft, and means operatively connecting the rotor shaft with the motor for effecting a road milling operation, said adjustable carriages permitting adjustment 25 of the depth of cut of the rotor teeth.

4. In a road miller, a main frame having spaced bars, wheels carried by the main frame at its forward end, a motor carried by the main frame between the bars and having a universal joint, a 30 sub-frame carried by the main frame at right angles thereto, runner frames associated with the sub-frame and the main frame and disposed in parallel spaced relation to each other, means operatively connecting the runner frames with 35 the sub-frame, means carried by the main frame and operable for raising and lowering the runner frames with respect to the sub-frame and the main frame, carriages carried by the runner frames, a rotor having a shaft extending between 40 the runner frames and having end portions journaled in the carriages, a mounting frame having end portions journaling the end portions of the rotor shaft, opposite corresponding end portions of the mounting frame being pivotally connected 45 to the universal joint, teeth carried by the rotor, bearing standards carried by the mounting frame and disposed above the rotor, bearings carried by the bearing standards, a differential having shafts with their end portions journalized in the last mentioned bearings, means operatively connecting the 50 shafts with the rotor shaft, means connecting the shafts with the motor for conducting rotative movement through all of said shafts to the rotor for rotating said rotor and engaging the teeth thereof in a road milling operation, and means carried by the runner frames and carriages for shifting said carriages with respect to the runner frames whereby the depth of cut of the rotor teeth may be adjusted.

60. 5. In a road miller, a rotor tooth comprising mating sections, means connecting said sections to each other and binding said sections as a unitary tooth in tight frictional engagement about a rotor shaft, and tooth points removably connected with the tooth sections.

65. 6. In a road miller, a rotor tooth comprising mating tooth sections having hemispherical portions and tooth members extending in opposite directions and in parallel longitudinal planes, means connecting the tooth sections and binding 70 said sections as a unit in tight frictional engage-

ment about a rotor shaft, and tooth points carried by the tooth members and engageable with a surface to be milled upon rotation of the tooth and rotor shaft.

7. In a road miller as recited in claim 6, 5 wherein the means comprises bolts extending through flanges on the tooth sections and through the inner end portions of the tooth members, springs surrounding the bolts, and nuts compressing the springs and urging the tooth sections 10 toward each other.

8. In a road miller, a main frame having spaced bars, a motor carried by the main frame between the bars, wheels for the main frame, a universal joint for the motor, a sub-frame carried by the 15 main frame and being disposed at right angles to said main frame, rods carried by the sub-frame, raising levers carried by the rods, hydraulic mechanism carried by the main frame and including a hydraulic jack cylinder, a piston and 20 a cross head, cables operatively connecting the cross head with the raising levers, runner frames, levers connecting the rods with the runner frames, said raising lever and last mentioned levers and the rods raising the runner frames 25 with respect to a surface to be milled upon operation of the piston of the hydraulic mechanism, carriages carried by the runner frames, means for adjusting the carriages vertically on the runner frames, said carriages having hub 30 portions, a rotor having a shaft having its end portions journaled in the hub portions of the carriages, a mounting frame swingingly connected with the universal joint and having end portions journaling the end portions of the rotor 35 shaft, teeth carried by the rotor shaft, bearing standards carried by the mounting frame, bearings carried by the bearing standards, a differential having shafts with their end portions journaled in the last mentioned bearings, sprockets 40 carried by the last mentioned shafts, sprockets carried by the rotor shaft, sprocket chains operatively connecting the sprockets, and a drive shaft connecting the differential with the motor, said drive shaft and differential shaft transmitting rotative movement through the sprockets and sprocket chains to the rotor for rotating said 45 rotor whereby the rotor teeth will be caused to effect a road milling operation, vertical adjustment of the carriages effecting adjustment of 50 the depth of cut of the rotor teeth.

9. In a road miller, a main frame, a sub-frame carried thereby, runner frames carried by the sub-frame, rotatable milling means carried by the runner frames, a power source on the main frame for rotating the milling means, and hydraulically operated means carried by the main frame and operable for shifting the runner frames and milling means with respect to the 55 sub-frame and main frame.

10. In a road miller, a main frame, a sub-frame carried thereby, runner frames carried by the sub-frame, milling means rotatably mounted on the runner frames and adjustable thereon, a power source on the main frame for rotating the 60 milling means, and hydraulically operated means carried by the main frame and operable for shifting the runner frames and milling means with respect to said main frame and sub-frame.
